Letters Patent No. 1871-Dated Dec. 14, 1869.

Design for Stove Plates.

The schedule referred to in these Letters Patent and making part of the same.

To all whom it may concern:

Be it known that we, Daniel E. Paris, and A. S. Wedder, each of the City of Troy, in the County of Rensselaer and State of New York, have jointly invented or produced a new and original ornamental Design for Stove Plates; and we do hereby declare that the following is a full and exact description of the same, reference being had to the annexed photographic drawing of a stoveplate bearing our said ornamental design.

This new ornamental design for stove plates consists of a compound ornament composed of a partially pitted, oval or circular bed *o. o.* covered in the middle by an oval or circular shield, *p.*, having branches, *q. q.* *q. q.* extended through, and others *o. o.* reaching over the said bed *o. o.* and connected with heads, *s. s.*; and also having other radial branches, *t. t.*, extending to and terminating in lateral heads, *u. u.* bearing pendants, *v. v.* all the parts being shaped and arranged together and upon a plain panel, *W. W.* so as to have the appearance shown by the annexed photographic drawing.

What we claim as new and of our invention, and desire to secure by Letters Patent, is the herein described ornamental design for Stove Plates.
